HAND STARTER FOR INTERNAL COMBUSTION ENGINES

Albert M. Porter, Newton, Kans.

Application November 15, 1941, Serial No. 419,331

3 Claims. (Cl. 123—185)

This invention relates to a hand starter for internal combustion engines, and has for its principal object the provision of a mechanism that is hand operated for giving an initial motion to an engine for starting of the same, said mechanism being connected to the engine in working relation to the engine's flywheel ring gear.

A further object of this invention is to provide a hand operated starter for engines such as are employed on tractors, stationary engines, Diesel engines, and marine engines, said starter having a crank and gear arrangement to turn the flywheel of the engine whereby little strength is required to start large engines of the above mentioned type.

A still further object of this invention is to provide a starter having safety features to prevent a direct kick on an operator's arm while cranking an engine should the engine backfire, which heretofore occasionally resulted in broken arms; and furthermore to provide a starter that will automatically disengage from the flywheel when the engine has started in motion.

These and other objects will hereinafter be more fully explained, reference being had to the accompanying drawings forming a part of this specification, and in which like characters will apply to like parts in the different views.

Referring to the drawings:

Fig. 1 is a longitudinal sectional view of the starter and method of attaching the same to an engine, said engine being fragmentarily shown.

Fig. 2 is an end view of the starter, parts removed for convenience of illustration.

Fig. 3 is a side view of the starter.

This invention herein disclosed relates to a hand starter for internal combustion engines, and more particularly to large engines which require great power to start the same, and which are equipped with a flywheel ring gear 1 that is secured to the rear end of the crank shaft for the engine (said crank shaft not being shown in the drawings). Said ring gear 1 is generally positioned at the rear of the engine block 2 and in the transmission housing 3 that encloses the said ring gear 1.

The block has the usual offset or extension 4 and an opening 5 provided therein through which connection is made with the ring gear for starting of the engine. The object of my invention is to turn the ring gear by hand operation, and it is commonly known that an engine is turned by a crank axially secured to an end of the crank shaft, but due to the great compression of the engine much force or strength is required to turn the engine so that the same will start, and occasionally there is a backfire in the engine which may cause operator's arms to be broken by the reversed turns of the engine, and furthermore there are engines equipped with electrical-

ly operated starters which lack efficiency in certain fields in which the engine is put to work. In such cases my invention may be adopted to perform a satisfactory result.

5 My invention consists of a cylindrical starter housing 6, being open at each end, the longitudinal axis of said housing being in parallelism with the engine, and illustrated in the drawings at the right side of the engine. One open end 10 of the starter housing is placed in registry with the opening 5 in the extension of the engine block, and said end of the housing has a flange 7 to secure the starter housing to the extension 4 by bolts 8 passing through the flange 7 and threadedly engaging in the extension. The outer end of the starter housing has a plate 9 to close said end after assembly of the starter parts have been completed.

Axially positioned in the starter housing is a 20 rotatable sleeve element 10 and adjacent the outer end of the sleeve is a bevel gear 11 integral therewith as turning means for said sleeve element. The forward end of said sleeve element is carried by a wall 12 that is integrally joined to the inside of the housing wall, said wall 12 having a hub 13 to receive last said end of the sleeve element, and said sleeve element having a shoulder 14 to engage against the outer side of said wall 12 by which means an inner longitudinal movement of the sleeve element will be avoided. The other end of the sleeve element is supported rotatably by a bearing 15 having an opening to receive said end of the sleeve and said bearing to engage against the outer side of the 25 bevel gear 11, said bearing 15 being secured to the inside wall of the starter housing by bolts 16 that extend through the wall of the starter housing and threadedly engage in a base 17 which is integrally joined to one end of the bearing 15; 30 the sleeve being so carried will be void of longitudinal movement but will be free to rotate as turned by the bevel gear 11.

Traversely positioned to said gear 11 and in mesh therewith is another gear 18, said gear 45 18 having one end of a shaft 19 integral therewith, the other end of said shaft 19 extending outward through the side wall of the starter housing, there being a hub 20 extending inwardly from the housing to engage against the 50 outer side of the gear 18 to properly retain said gear in mesh with gear 11, and a hub 21 outwardly extending from the housing through which the shaft 19 extends. In said hub 21 is positioned a packing 22 that is compressed 55 against the shaft by a gland nut 23 threadedly engaging said hub 21, whereby the packing material around the shaft will prevent oil leakage outward from the starter housing.

It will be seen that the free end of the shaft 60 19 is secured to a clutch mechanism which is

turned by a crank element 24, the clutch mechanism consisting of a cylindrical member 25 that has a bore in each end thereof, one bore to receive the free end of the shaft 19 and secured by a cotter pin 26 passing through said member 25 and through said shaft 19, the other end of the member 25 having a face plate 27 integral therewith to frictionally engage against the face of plate 28, said plates being tensioned together by an annular collar 29 that engages on the outer side of plate 27 and having an opening to receive the cylindrical member 25. Passing through the outer extremity of the plate 28 and the collar 29 are bolts 30 on which are positioned coil springs 31 to engage against the collar and properly tensioned by nuts 32 threadedly engaging on the threaded end of the bolts, the purpose of the clutch mechanism being later described.

To axially align the clutch plates it will be seen that plate 28 has a cylindrical extension 33 to engage in the bore adjacent the plate 27. Outwardly extending from clutch plate 28 is a socket element 34, the recess in said element being preferably square or hexagonal to receive the bent end 35 of the crank element, and being secured from removal by a cotter pin 36 that engages through the wall of the socket element and through the bend 35 of the crank.

Now it will be seen that when the crank is turned, the clutch and bevel gears will be turned thereby rotating sleeve element 10, which is threaded internally to receive the threaded portion of a shaft 37, each end of which extends outward from its respective end of the sleeve element, the inner end of the shaft being adjacent the opening in the extension 4 and having a starter gear 38 mounted thereon, the teeth of which are adapted to slide in mesh with the teeth of the ring gear 1 as turning means for the ring gear.

Eccentrically positioned on the other end of the threaded shaft 37 is a weight member 39 which is secured to the shaft by a set screw 40. In Fig. 1 the weight and crank element are shown horizontally for convenience of illustration, however in an idle period they will be vertically positioned. When the sleeve is turned, the threaded shaft by reason of the weight will not rotate immediately but will be moved longitudinally by the threaded engagement, which in turn will cause gear 38 to slide in mesh with the ring gear 1. When said gears are properly engaged the longitudinal movement of the shaft 37 will be stopped by the weight member 39 engaging against the outer end or shoulder A of the sleeve element, at which time, the threaded shaft will rotate with the sleeve element to turn the ring gear 1 for the purpose of starting the engine. As soon as the engine starts running the threaded shaft will revolve with a greater speed than the sleeve element, and by means of the threaded engagement of the shaft and sleeve, the threaded shaft will be moved outward to disengage the starter gear 38 from ring gear 1 instantly, and when the gear 38 is thrown out of mesh the same will strike against a spring 41, that is positioned over hub 13 to function as a cushion for said gear 38.

The purpose of the clutch mechanism will now be described. When the starter gear 38 is engaged with the ring gear 1 instead of the engine

starting immediately the same may back fire causing a reverse turn of the starter, and if this occurs the clutch will permit sliding movement of the clutch plates to function as a shock absorber to the person that has gripped the crank.

Modifications may be made as lie within the scope of the appended claims.

Having fully described my invention what I claim as new and desire to secure by Letters Patent is:

1. In a hand starter for internal combustion engines comprising a housing having two open ends, a threaded shaft centrally positioned in the housing, the ends of the shaft being adjacent their respective open ends of the housing, and an internally threaded sleeve member to receive said threaded shaft to move the shaft longitudinally when the sleeve is turned; means to rotatably carry said threaded sleeve member, a starter gear secured to one end of the threaded shaft adjacent one open end of the housing, and a plate to close the other end of the housing, a weight element eccentrically secured to the other end of the threaded shaft, a gear secured to the rotatable sleeve element and a gear in mesh therewith to turn the same, a crank and means to connect the crank to said last gear to turn the sleeve element.

2. In a hand starter for internal combustion engines comprising an elongated cylindrical housing being open at one end for connection purposes, a threaded sleeve element rotatably mounted in said housing and parallel therewith, a threaded shaft adapted to be moved longitudinally in said sleeve when said sleeve is turned, an eccentrically positioned weight member secured to one end of the shaft to restrict the longitudinal movement thereof in one direction, and a starter gear mounted on the other end of the shaft to restrict the movement the other direction, a coil spring positioned on the sleeve element adjacent the gear as cushion means for the gear in its movement theretoward, a gear secured to the end of the sleeve opposite the spring, and a gear transversely positioned to said last gear to turn the same, a shaft axially secured to said last gear and extending through and outward of the side of the starter housing, a clutch and means to secure the same to the free end of said last shaft, and a crank element secured to the clutch to turn the same.

3. In a hand starter to turn the ring gear of internal combustion engines comprising a starter housing secured in close proximity to the periphery of the ring gear of the engine, an internally threaded sleeve member rotatably arranged in said housing, a threaded shaft to threadedly engage in the threaded sleeve to move longitudinally toward the periphery of the ring gear, a gear secured to one end of the shaft to engage said ring gear when the shaft is moved theretoward, a weight element secured on the other end of the shaft to lock the shaft with the sleeve to turn the gear, a pair of bevel gears to turn the rotatable sleeve element, one gear being secured to the rotatable sleeve element the other gear having a shaft extending outward through the wall of the housing, a crank and shock absorbing means to connect the crank to said last shaft to turn the bevel gears.

ALBERT M. PORTER.
